US0D1084314S

(12) **United States Design Patent** (10) **Patent No.:** **US D1,084,314 S**
(45) **Date of Patent:** **** Jul. 15, 2025**

(54) **RESPIRATORY INTERFACE AND CIRCUIT STORAGE ACCESSORY**

(71) **Applicant:** **Fisher & Paykel Healthcare Limited**, Auckland (NZ)

(72) **Inventors:** **Andrew William White**, Auckland (NZ); **Mehak Iqbal Janjua**, Auckland (NZ); **Emeric Henri Michel Belleux**, Auckland (NZ); **Hugo Max Treherne James**, Christchurch (NZ); **Jason Allan Klenner**, Auckland (NZ); **Mustafa Basil Taha**, Auckland (NZ)

(73) **Assignee:** **Fisher & Paykel Healthcare Limited**, Auckland (NZ)

(**) **Term:** **15 Years**

(21) **Appl. No.:** **29/946,768**

(22) **Filed:** **Jun. 11, 2024**

(57) **CLAIM**

The ornamental design for respiratory interface and circuit storage accessory, as shown and described.

DESCRIPTION

FIG. 1 shows a top, front and right side perspective view of the respiratory interface and circuit storage accessory embodying our design.

FIG. 2 shows a bottom, rear and left side perspective view thereof.

FIG. 3 shows a front view thereof.

FIG. 4 shows a rear view thereof.

FIG. 5 shows a left side view thereof.

FIG. 6 shows a right side view thereof.

FIG. 7 shows a top view thereof; and,

FIG. 8 shows a bottom view thereof.

The broken lines show portions of the respiratory interface and circuit storage accessory that form no part of the claimed design.

1 Claim, 8 Drawing Sheets
